UNITED STATES PATENT OFFICE.

AUSTIN A. HOLBECK, OF CLEVELAND, OHIO, ASSIGNOR TO CHARLES A. BRAUCHLER,
OF CANTON, OHIO.

FUEL-FEEDER.

1,206,112.

Specification of Letters Patent. Patented Nov. 28, 1916.

Application filed December 27, 1913. Serial No. 809,100.

To all whom it may concern:

Be it known that I, AUSTIN A. HOLBECK, a citizen of the Dominion of Canada, residing at Cleveland, in the county of Cuyahoga and State of Ohio, have invented new and useful Improvements in Fuel-Feeders, of which the following is a specification.

The invention relates to a fuel feeder, and more particularly to the class of devices for 10 distributing pulverized coal to small or large furnaces.

The primary object of the invention is the provision of a device of this character wherein the pulverized coal will be uniformly distributed to one or more furnaces 15 to be burnt, the unspent coal being returned to the container therefor.

Another object of the invention is the provision of a device of this character wherein 20 the feed of the coal is automatically regulated.

Another object of the invention is the provision of a device of this character wherein the pulverized coal is automatically fed to the respective furnaces for the distribution of fuel thereto, the feeding of the fuel being controlled so as to avoid the adjustment of the valves of the furnaces, and the surplus coal which is not required by 25 30 any of the furnaces being returned, thereby permitting continuous operation and preventing the pipes from becoming clogged.

A still further object of the invention is the provision of a device of this character 35 which is simple in construction, thoroughly reliable and efficient in operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings, Figure 1 is a side elevation of a device constructed in accordance with the invention applied to a series of furnaces. Fig. 2 is a vertical sectional view through the device and one of the furnaces.

Similar reference characters indicate corresponding parts throughout the several 50 views in the drawings.

Referring to the drawings in detail, the numerals 5, 6 and 7 designate furnaces which are similarly constructed and are of any ordinary well-known type, each having a 55 smoke flue 8, it being understood of course that a greater or less number of furnaces can be operated with the device hereinafter fully described.

At any desirable point spaced from the 60 furnaces is a coal bin 9, which is adapted to contain pulverized coal, and is supported upon uprights 10 at the required height from the foundation. Formed in the bottom of the bin 9 is a discharge chute 11 in 65 which is arranged a feed or screw conveyer 12, the chute being in communication with a delivery hopper 13 having its discharge mouth 14 located directly above a revolving or turn table 15, the stem or spindle 16 of 70 which is suitably journaled and is connected with a driving motor 17 of any preferred type.

Arranged above the bin 9 is a funnel-shaped collector 18, the discharge end 19 of 75 which extends into the bin and is adapted to deliver unspent fuel thereto, the unspent fuel being extracted from the air which conveys the same from the furnaces in a manner presently described.

Contiguous to the turn table 15 is a blower or fan 20 with which communicates a suction conduit 21, the intake end 22 of which is extended upwardly beneath the turn table 15 near the periphery thereof, while 85 mounted upon the delivery mouth 14 of the hopper 13 is an arm 23 supporting a wiper 24 which contacts with the upper surface of the turn table 15 and is designed to wipe off the powdered coal therefrom for the deposit 90 of the same in the suction conduit 21 so that the blower or fan will distribute the powdered coal to the furnaces in a manner presently described.

Leading from the periphery of the blower 95 or fan 20 is a distributing pipe 25, which constitutes a continuation of the conduit 21, the horizontal portion 26 of said pipe 25 being disposed above the furnaces 5, 6 and 7, while communicating with and depending 100 from this pipe 26 are a series of inlet pipes 27 which also communicate with the furnace

for supplying the powdered coal, and these latter pipes 27 can be construed as continuations of the suction conduit.

The pipe 26 has connected thereto a 5 turn pipe 29 which leads to the collector 18 and is adapted to convey the unspent coal into the collector which is separated from the air and again discharged into the bin to be subsequently fed to the furnaces.

10 The intake pipes 27 each is provided with a valve 30, the stem 31 of which carries a sprocket wheel 32 over which is trained a sprocket chain 33 which depends therefrom in convenient reach above the foundation on 15 which the furnaces are supported so that the valves can be manually manipulated for shutting off the intake pipes 27 or regulating the feed therethrough.

Extending from the top of the collector 20 18 and communicating with the suction pipe 21 is an air suction pipe 34, the same being formed contiguous to its union with the suction pipe 21. This pipe permits the air from the container 18 to return to the suction side 25 of the fan or blower 20.

Mounted upon the suction pipe 21 is a bearing 35 which supports a rocking arm 36 fulcrumed upon the bearing 35, the lever being also connected with a depending rod 30 37 which is slidably passed through the suction pipe 21 and has formed on its lower end a float 38, the latter being inclosed within a cage 39 communicating with and depending from the suction pipe 21, the cage 39 35 being open at its bottom and extends within a well 40, formed in the foundation. The well contains liquid 41 which is subjected to suction from the suction pipe 21 so as to 40 displace the same and thereby operate the float 38 for raising and lowering of the arm 36.

The arm 36 is pivotally connected to the arm 42, which is connected to the arm 43 45 of an electric speed controller 44, which is in circuit with the motor 17, and in this manner the speed of the motor 17 will be regulated simultaneously with the raising or lowering of the float 38 so that on opening the valves 30 the increased suction will 50 cause the raising of the liquid within the well 40, thereby lifting the float 38 to operate the controller and increase the speed of the motor 17, increasing the feed to the furnaces, and on the closing of the valves 30 55 the reduction of the suction will regulate the speed of the motor 17 to decrease the feed of coal to the furnaces. It will be apparent that should any one of the furnaces be cut off from the supply of fuel this reduces the amount of air delivered to the fan and therefore reduces the suction in the pipe 21 and allows the liquid 41 in the well to lower and with it the float 38 which adjusts the controller 44 automatically and at the 60 same time reduces the speed of the motor 17, 65

and thus decreases the fuel supply to the furnaces.

From the foregoing, it is thought that the construction and manner of operation of the device will be clearly apparent, and therefore a more extended explanation has 70 been omitted.

By the words "fuel-consuming devices" in my claims, I intend to cover a plurality of burners or fuel-consuming devices, 75 whether they operate in connection with a single heating chamber or in connection with a plurality of heating chambers.

What is claimed is:—

1. The combination with a fuel supply, 80 of a conduit adapted to receive material from the fuel supply for delivering it to a furnace, means for supplying a fluid to the conduit, means for delivering the fuel from the fuel supply to the conduit, a controller for said means, means automatically operated by a variance in the density of fluid within the conduit for actuating the controller, and means including a pipe connected with the conduit for returning the 85 unspent material to the fuel supply. 90

2. The combination with a fuel supply, of a conduit adapted to receive material from the fuel supply for delivering it to a furnace, means for supplying a fluid to the conduit, means for delivering the fuel from the fuel supply to the conduit, a controller for said means, means automatically operated by a variance in the density of fluid within the conduit for actuating the controller, 95 means including a pipe connected with the conduit for returning the unspent material to the fuel supply, and means located between the conduit and the furnace for regulating the supply of material from said conduit to the furnace. 100 105

3. The combination with a furnace, of a container, feed mechanism arranged for feeding fuel from the container, a conduit adapted to receive material from the feed mechanism for delivering it to the furnace, a motor connected with the feed mechanism, a controller for the said motor, means for supplying a fluid to the conduit, means automatically regulated by a variance in the density of fluid within the conduit for actuating the controller, a collector for communication with the container, and a return pipe connected with the conduit and the said collector. 110 115 120

4. The combination with a furnace, of feed mechanism arranged for feeding fuel, a conduit adapted to receive material from the feed mechanism for delivering it to the furnace, a motor connected with the feed mechanism, a controller for the said motor, means for supplying fluid to the conduit, means automatically regulated by a variance in the density of fluid in the conduit for actuating the controller, a collector inter- 125 130 135

posed between the conduit and the feed mechanism, and a pipe connected with the conduit and the collector for returning unspent fuel to the latter from the said conduit.

5. The combination with a furnace, of a container, feed mechanism arranged for feeding fuel from the container, a conduit adapted to receive material from the feed mechanism for delivering it to the furnace, a motor connected with the feed mechanism, a controller for the said motor, means for supplying a fluid to the conduit, means automatically regulated by a variance in the density of fluid within conduit for actuating the controller, means located in the conduit for regulating the supply of material to the furnace, and a return pipe connected with the conduit for delivering unspent fuel therefrom to the container.

20 therefrom to the container.

6. A fuel distributing mechanism for furnaces comprising means for the feeding of fuel, a conduit arranged to receive fuel from the feed means, means for distributing fuel
25 from the conduit to the furnaces, means for directing a volume of fluid through the conduit and distributing means, a motor for driving the feed means, a controller for regulating the speed of the motor, means
30 operative on a variance in the density of the fluid within the conduit for actuating the controller, means for regulating the distribution of fuel from the distributing means to the furnaces, and a pipe communicating
35 with the conduit for returning the unspent fuel therefrom to the feed means.

7. A fuel distributing mechanism for furnaces comprising a fuel container having a discharge way, means in the discharge way
40 for the feeding of fuel from the container, a conduit arranged to receive fuel from the discharge way, means for distributing fuel from the conduit to the furnaces, means for directing a volume of fluid through the conduit and distributing means, a motor for
45 driving the feed means, a controller for regulating the speed of the motor, means operative on a variance in the density of the fluid within the conduit for actuating the controller, means for regulating the distribution of fuel from the distributing means to the furnaces, a pipe communicating with the conduit for returning the unspent fuel therefrom directly to the container, and
50 means for extracting fluid from the unspent fuel and directing it into the conduit.

8. The combination with a furnace, of a fuel bin having a delivery chute, a feed device arranged for feeding fuel from the chute, a conduit adapted to receive fuel from the feed device, a distributing pipe connected with the conduit and having a lead directed to the furnace, a well containing fluid, a cage communicating with the conduit and projected into the well, a mo-

tor connected with the feed device, a controller for regulating the speed of the motor, a float within the cage and controlled by the fluid in the well, connection between the float and the controller for automatically regulating the latter on the rise and fall of the fluid in the well, and means for supplying a fluid to the conduit. 70

9. The combination with a furnace, of a
fuel bin having a delivery chute, a feed de- 75
vice arranged for feeding fuel from the
chute, a conduit adapted to receive fuel
from the feed device, a distributing pipe
connected with the conduit and having a
lead directed to the furnace, a well contain- 80
ing fluid, a cage communicating with the
conduit and projected into the well, a motor
connected with the feed device, a controller
for regulating the speed of the motor, a
float within the cage and controlled by the 85
fluid in the well, connection between the
float and the controller for automatically
regulating the latter on the rise and fall of
the fluid in the well, means for supplying a
fluid to the conduit, and means located in 90
the lead from the distributing pipe to the
furnace for regulating the fuel supply to the
latter. 90

10. The combination with a furnace, of
a fuel bin having a delivery chute, a feed 95
device arranged for feeding fuel from the
chute, a conduit adapted to receive fuel
from the feed device, a distributing pipe
connected with the conduit and having a
lead directed to the furnace, a well contain- 100
ing fluid, a cage communicating with the
conduit and projected into the well, a motor
connected with the feed device, a controller
for regulating the speed of the motor, a float 105
within the cage and controlled by the fluid in the well, connection between
the float and the controller for automatically
regulating the latter on the rise and fall
of the fluid in the well, means for supplying 110
a fluid to the conduit, means located in
the lead from the distributing pipe to
the furnace for regulating the fuel supply
to the latter, and a return pipe connected
with the distributing pipe for conveying the
unspent fuel therefrom to the bin. 115

11. The combination with a furnace, of a fuel bin having a delivery chute, a screw feed device arranged within the chute for feeding fuel from the bin, a turn table located contiguous to the screw feed device for receiving fuel therefrom, a suction conduit having one end adapted to receive fuel from the turn table for delivering it to the furnace, a well containing fluid, a cage communicating with the suction conduit and projected into the well, a float in the said cage, a motor for operating the feed screw device, a speed controller for the motor, a connection between the float and the controller for automatically regulating the 120 125 130

- latter under the action of the fluid upon the float, and means for supplying a fluid to the conduit.
12. The combination with a furnace, of a fuel bin having a delivery chute, a screw feed device arranged within the chute for feeding fuel from the bin, a turn table located contiguous to the screw feed device for receiving fuel therefrom, a suction conduit having one end adapted to receive fuel from the turn table for delivering it to the furnace, a well containing fluid, a cage communicating with the suction conduit and projected into the well, a float in the said cage, a motor for operating the feed screw device, a speed controller for the motor, a connection between the float and the controller for automatically regulating the latter under the action of the fluid upon the float, means for supplying a fluid to the conduit, and means for regulating the supply of fuel from the conduit to the furnace.
13. The combination with a furnace, of a fuel bin having a delivery chute, a screw feed device arranged within the chute for feeding fuel from the bin, a turn table located contiguous to the screw feed device for receiving fuel therefrom, a suction conduit having one end adapted to receive fuel from the turn table for delivering it to the furnace, a well containing fluid, a cage communicating with the suction conduit and projected into the well, a float in the said cage, a motor for operating the feed screw device, a speed controller for the motor, a connection between the float and the controller for automatically regulating the latter under the action of the fluid upon the float, means for supplying a fluid to the conduit, means for regulating the supply of fuel from the conduit to the furnace, a collector for communication with the bin, and a return pipe connected with the conduit and the said collector.
14. The combination with a furnace, of feed means arranged for feeding fuel, a conduit adapted to receive fuel from the feed means for delivering it to the furnace, a motor connected with the feed means, a controller for the said motor, means for supplying a fluid to the conduit, means automatically regulated by a variance in the density of fluid within the conduit for actuating the controller, means located in the conduit for regulating the supply of material to the furnace, a collector for communication with the feed means, and a return pipe connected with the conduit and the said collector.
15. In an apparatus for feeding pulverized fuel to furnaces, the combination of a conveyer having a closed circuit, means for circulating a gas through said circuit, means controlled by the pressure in the circuit for introducing pulverized fuel into the circu-
- lating gas and means for delivering fuel from the circuit to the furnaces.
16. In an apparatus for feeding pulverized fuel to furnaces, the combination of a conveyer having a closed circuit, means for circulating a gas through said circuit, means for delivering fuel to the circuit, a controller for said fuel delivering means, means automatically operated by a variance in the density of the gas within the circuit for actuating the controller, and means for delivering fuel from the circuit to the furnaces.
17. In a system of the character described, one or more fuel consuming devices, a conduit having a branch leading to each consuming device, means for forcing a gaseous fluid through such conduit, and means for introducing powdered fuel to the conduit in advance of the branches leading to the consuming devices, said conduit at a point beyond the consuming devices freely discharging outside the gaseous current, the fuel which passes beyond and is not consumed in said consuming devices.
18. In a powdered fuel feeder, a fuel consuming device, a conduit having a branch leading thereto, means for forcing a gaseous fluid through said conduit, means for introducing powdered fuel into the gaseous current in advance of said branch leading to the fuel consuming device, and a separator to which the conduit leads at a point beyond said branch, said separator being arranged to separate from the fluid the fuel which passes along the conduit beyond the said branch.
19. In a powdered fuel feeder, a plurality of fuel consuming devices, a conduit having branches leading thereto, means for forcing a gaseous fluid through said conduit, means for introducing powdered fuel into the gaseous current in advance of the branches leading to the fuel consuming devices, and a separator to which the conduit leads at a point beyond the branch conduits, said separator being arranged to separate from the fluid the fuel which passes beyond and is not consumed by the fuel consuming devices, together with means for returning the fuel from said separator to the fuel introducing means.
20. In a powdered fuel feeder, the combination of a feed hopper, a dust collector arranged to discharge into the hopper, a plurality of fuel consuming devices, a fuel supply pipe having branch pipes leading to the respective fuel consuming devices, means for forcing a current of air through said fuel supply pipe, and for feeding fuel from the hopper into said current of air, said fuel supply pipe having a connection with the dust collector at a point beyond the fuel consuming devices and receiving the air and fuel which pass beyond the latter, and valves in the branch fuel pipes.

21. The combination with a plurality of fuel consuming devices, of a conduit communicating therewith to supply fuel thereto, means for forcing air and powdered fuel through said conduit, a separator to which said conduit leads at a point beyond the fuel consuming devices, and arranged to separate the air and fuel which pass beyond the latter, and means whereby the fuel separated by the collector may be returned into the fuel conduit.
22. In combination with a plurality of fuel consuming devices and a conduit communicating therewith adapted to supply fuel thereto, means for forcing fluid through said conduit, fuel feeding means for feeding fuel into the conduit in advance of the fuel consuming devices, a hopper for supplying fuel to said fuel feeding means, a collector connected to the conduit beyond the fuel consuming devices and discharging into the hopper, and a pipe connecting the collector to the conduit at a point in advance of the fuel consuming devices.
23. In a system of the character described, one or more fuel consuming devices, a conduit having branches leading to said consuming devices, means for forcing a gaseous fluid through said conduit and for supplying powdered fuel to the gaseous fluid in advance of said branches, a separator to which the conduit leads at a point beyond said branch, said separator being arranged to separate from the fluid the fuel which passes along the conduit beyond the branches leading to the fuel consuming de-
- vices, valves for controlling communication between the conduit and the fuel consuming devices, and means operative upon the adjustment of the valves for regulating the supply of fuel to the conduit.
24. In combination with a plurality of fuel consuming devices, a conduit for supplying fuel thereto, means for closing or establishing communication between the conduit and the fuel consuming devices, means for supplying fuel to the conduit, a controller therefor, and means whereby said controller is actuated when a fuel consuming device is connected to or disconnected from the conduit.
25. In a powdered fuel feeder, the combination of a hopper, a dust collector arranged to discharge into the hopper, a fuel supply pipe into which the hopper discharges, a series of furnaces adjacent to the fuel supply pipe, nozzles leading into the furnaces, branch fuel pipes connecting the fuel pipe and nozzles, valves in the branch fuel pipes, said fuel supply pipe having a portion beyond said branch fuel pipes discharging into said collector, and means whereby the fuel received in said collector may be returned to the fuel supply pipe after being separated from the air.

In testimony whereof I affix my signature in presence of two witnesses.
